UNITED STATES PATENT OFFICE.

PETE BERNARD, OF PHILADELPHIA, PENNSYLVANIA.

TABLE ACCESSORY.

Application filed October 7, 1926. Serial No. 140,077.

This invention relates to a structure which may be designated as a table accessory, the same having more particular reference to a device for dispensing sugar and napkins.

More specifically, the invention has reference to a structure of the class specified which is adapted more particularly for use on tables, counters, and the like in lunch rooms, restaurants and similar public eating places and it includes a combination sugar bowl and napkin containing and dispensing box.

The invention comprises a base plate, standards rising from the four corners thereof and means in the upper ends of the standards for supporting the sugar bowl and the napkin box.

Other structural features and advantages derived from their particular association will become apparent from the following description and drawing.

In the drawings:—

Figure 1 is a front elevation of the complete device.

Fig. 2 is a central vertical section through the same, the section being taken approximately upon the plane of the line 2—2 of Fig. 1.

Fig. 3 is a top plan view with a portion broken away and shown in section.

Fig. 4 is a detailed view.

Referring to the drawings in detail the reference character 1 designates the base plate which is of general rectangular configuration, the same being provided on its bottom with appropriately shaped rests or feet 2, these being arranged on the four corners and being provided with screw-threaded sockets. The standards 3 have screw-threaded lower ends which are capped into the sockets and stop collars 4 rest in the top of the base plate. Additional stop collars 5 are carried by the upper end portions of the standards and a sugar bowl ring 6 is supported from these collars through the medium of radiating arms 7. The arms have openings through which the upper end extensions 8 of the standards pass. The sugar bowl 9, which is of suitable ornamental configuration is provided with an outstanding rim which rests upon the ring.

The bowl, of course, has a removable cover 10. Moreover, it is provided at its bottom with a discharge nozzle 11 disposed at a suitable elevation above the base plate 1 and provided with a regulating valve 12. The valve is equipped with suitable finger pieces by means of which it is conveniently operated.

The napkin box is represented by the reference character 6, this being of square design and of an appropriate proportion for containing the paper napkins 14 in the customary superposed relation. The box is open at its top and this open top is closed by a removable cover 15. At the four corners of the box are vertically disposed sleeves 16 which surround the extensions 8 on the upper ends of the aforesaid standards. The front wall of the box is provided with a slot 17 through which the napkins are dispensed in a step-by-step manner. A feed shaft 18 is mounted in the bottom of the box adjacent the slot for feeding the napkins outwardly through the discharge slot. This shaft is, of course, provided with a conveniently located knob or handle 19, by means of which it is rotated.

In practice, it is understood that in using the sugar bowl the cup is placed beneath the discharge nozzle and the valve is opened, permitting sugar to flow, by gravity, into the cup. Then the valve is closed when a suitable quantity of sugar has been obtained. In using the napkin holder the rotary shaft is turned to feed the napkins out one by one. If desired, a weight (not shown) may be located in the napkin box to cause the napkins to be more easily dispensed. The base plate 1 is of a size to permit salt and pepper shakers to be placed thereon without interference to the use of the sugar bowl.

It is believed that by considering the description in connection with the drawings, a clear understanding of the construction and operation of the invention will be obtained. In view of this, a more lengthy description is thought unnecessary.

Minor changes coming within the field of invention claimed may be resorted to if desired.

I claim:—

In a structure of the class described, a

plurality of standards, means for holding the standards in upright positions, a ring having apertured arms receiving the upper ends of the standards, said standards being provided with shoulders on which the arms of the ring rest, a sugar bowl extending downwardly through said ring and provided with a peripheral rim resting upon

said ring, and a box having sleeves surrounding the upper ends of said standards, said box resting upon said sugar bowl to hold the same in place within the ring and to hold the ring against accidental displacement from the standards.

In testimony whereof I affix my signature.
PETE BERNARD.
